UNITED STATES PATENT OFFICE

139,821

DESIGN FOR A PNEUMATIC RIVETING HAMMER UNIT

Ernest Forss, Rockford, Ill., assignor to Nils F.
Testor, Rockford, Ill.

Application January 10, 1944, Serial No. 112,205

Term of patent 14 years

(Cl. D54—14)

To all whom it may concern:

Be it known that I, Ernest Forss, a citizen of the United States, residing at Rockford, in the county of Winnebago and State of Illinois, have invented a new, original, and ornamental Design for a Pneumatic Riveting Hammer Unit, of which the following is a specification, reference being had to the accompanying drawing, forming part thereof.

In the drawing:

Fig. 1 is a side view of a pneumatic riveting hammer unit showing my new design;

Fig. 2 is a top plan view, and

Fig. 3 is a front view thereof.

I claim:

The ornamental design for a pneumatic riveting hammer unit, substantially as shown.

ERNEST FORSS.
